SPRINKLER

Haggie I. Cockman, P.O. Box 656, Sanford, Fla.

Filed July 7, 1959, Ser. No. 825,569

1 Claim. (Cl. 239—383)

This invention relates to sprinklers and particularly to a sprinkler adapted to the distribution of water to lawns for agricultural irrigation.

The general object of the invention is to provide an improved sprinkler.

A specific object of the invention is to provide a sprinkler of simple and inexpensive construction which will operate to distribute water evenly over a wide area, which is trouble-free and which closes and opens automatically.

The novel features which are believed to be characteristic of this invention are set forth with particularity in the appended claim. The invention itself, however, both as to its organization and method of operation, together with further objects and advantages thereof, may best be understood by reference to the following description taken in connection with the accompanying drawings, in which:

Fig. 1 is a side elevation of a sprinkler in accord with the invention, the sprinkler being closed with the water turned off;

Fig. 2 is a sectional view taken along line 2—2 of Fig. 4, the sprinkler being closed as in Fig. 1;

Fig. 3 is a similar sectional view but showing the sprinkler open as during operation thereof;

Fig. 4 is a plan view of the sprinkler;

Fig. 5 is a plan view of a blank for forming the cover and spinner member of the sprinkler;

Fig. 6 is a perspective view of an element embodied in the rotor of the sprinkler; and

Fig. 7 is a sectional view corresponding generally to the views of Figs. 2 and 3 but showing a sprinkler of modified construction.

As seen in Fig. 1, the sprinkler comprises a hollow stem 1 adapted to receive water under pressure, a sleeve or cap 2 mounted on the stem, and a sheet metal closure member 3 having a flat central portion 4 closing the upper end 5 of the cap and having reaction vane portions 6 and 7 extending outwardly of and curved downwardly from the central portion.

The closure member 3 is attached by means of outwardly crimped leg ends 8 and 9, as best seen in Fig. 2, to the upper end of a rotor 10 which is disposed in the vertical cylindrical bore 11 of the cap 2. The cap 2 is counterbored and widens out into an enlarged diameter cavity 12 toward its lower end 13, the cavity joining bore 11, or being separated therefrom, by a shoulder 14 defining the upper end of the cavity. The stem 1 is threadedly attached as at 15 to the cap 2, and the upper end 16 of the stem forms the lower end of cavity 12 in the assembled device.

Rotor 10 comprises a hollow cylindrical barrel portion 17 having a bore or passage 17' extending vertically therethrough with an outwardly extending lip ring 18 at its lower end, the diameter of the ring 18 being greater than the internal diameter of the smaller diameter bore 11 and less than that of the larger diameter counterbore of cavity 12 of cap 2, whereby the ring has a bear-

ing at 19 against the shoulder 14 when the sprinkler is operative as shown in Fig. 3.

The sprinkler includes suitable means, such as screw threads 20, for attachment to an external standpipe or other mounting and source of water under pressure, and when water under pressure is supplied into the bore 21 of stem 1, the rotor 10 is forced upwardly into the operative position of Fig. 3, the cover plate 3 being raised above upper end 5 of the cap, discharge apertures, such as aperture 22, being exposed above end 5, and ring 18 being engaged against shoulder 14 to limit the upward displacement of the rotor and to form a bearing. The water pressure introduced through the bore 21 of the stem is applied under ring 18 and under the central portion 4 of cover plate 3 and in each case provides raising force to the rotor. Water issues from the aperture 22, and from an opposite identical aperture, below the cover plate and in a generally horizontal direction and the issuing stream contact or play against the respective downwardly curled reaction vanes 6 and 7.

A comparison of Figs. 1 and 4 will show that the plate 3 extends horizontally outwardly from its center portion 4 in opposite directions which are aligned with the streams which issue from the discharge apertures. The flat outwardly extending arm portions 23 and 24 of the plate, accordingly, lie immediately above the water streams. The end portions of these arms are curled downwardly to form vanes 6 and 7 which extend in a generally diagonal direction across a portion of the respective stream. Specifically, the stream issuing under arm 23 takes substantially the direction and form indicated between broken lines 25 and 26 in Fig. 4, and a part of the stream is seen to be directed at vane 6, while a part of the stream adjacent line 26 would freely pass an edge of the vane at 27 except that deflection of the stream by the vane causes the whole stream to be deflected. In other words, the portions of the stream adjacent line 25 are deflected into the portions adjacent line 26. The amount of deflection of the streams by the vanes 6 and 7 depends upon the angle of the vanes with respect to the direction of the streams, the extent to which the vane engages the stream, the speed of rotation of the rotor and on other factors, while the distance to which the streams reach and the overall spray pattern depend on similar factors and on the pressure of the water supplied. The cover plate is formed of a sheet or thin plate metal, such as brass or copper sheet, which can be bent to suit the particular requirements of each installation.

If the spray pattern has less than the desired diameter, the vanes are slightly unrolled. If the ground area within the outer diameter of the spray receives too little water, the vanes, or at least one of them, are rolled tighter and curved further into the stream path. Contact of the streams with the vanes spreads the streams vertically and provides a spray which covers the area with substantially equal amounts of water on each square foot of the area.

It will be noted that the vanes are curved into generally cylindrical shape and that they are tapered in width providing respective narrow, pointed tip ends 28, 29 which curl under the respective stream of water, whereby the vanes have some of the characteristics of nozzles.

The construction of the sprinkler will be further understood from the plan view of a blank 30 for the cover plate shown in Fig. 5. The arm portions 23 and 24 extend outwardly from central portion 4, terminating in tapered tips 28 and 29. Broken lines 31 and 32 indicate the location at which the curling of the arms to form the vanes should start. Lines 31 and 32 corre-

spond, accordingly, with the locations so identified in Fig. 1 on the completed and assembled device.

The blank 30 as further seen in Fig. 5 has two slots 33 and 34 in the central portion 4 arranged to receive the leg ends 8 and 9, respectively, of the rotor 10, as hereinabove explained.

The rotor as shown in Fig. 6 comprises a main body or barrel portion 35 having a smooth vertical cylindrical outer surface 36 and a vertically extending bore or passage 17' therethrough. The outwardly extending lip ring 18 at the lower end of the rotor is preferably formed integrally therewith. At the upper end, a slot 37 passes laterally through the rotor dividing the upper end into a pair of opposite legs 38 and 39, and the uppermost ends of the legs are reduced to form the bendable tips, such as tip 9 terminating at its lower end in shoulder 40 against which plate 3 rests. The tips are proportioned to fit snugly through the respective plate openings 33 and 34, and the plate is rigidly held down against shoulder 40, and the corresponding shoulder of leg 38, when the tips are crimped outwardly above the plate as shown in Figs. 2 and 3.

The slot 37 extends below the level of shoulder 40 to form discharge aperture 22 and its opposite aperture 41. These apertures are completely housed within sleeve 2 when the sprinkler is at rest, as in Fig. 2, but are exposed above the upper end 5 of the sleeve when water pressure is applied to raise the rotor into the position of Fig. 3.

The modified sprinkler of Fig. 7 comprises a hollow stem 51, which may be identical to that shown in the first embodiment at 1, and a sleeve 52, a rotor 53 and a cover plate 54 which correspond generally with elements 2, 10 and 3, respectively, of the first embodiment. Sleeve 52 screws to stem 51 and has a cylindrical vertical bore 55 in which cylindrical rotor 53 is rotatably and slideably disposed. In the arrangement of Fig. 7, no lip ring is required at the lower end of rotor 53, nor is a counterbored cavity required as at 12 in Fig. 2.

The bore or passage 56 which extends upwardly in rotor 53 communicates with a pair of opposed discharge apertures, of which aperture 57 is shown. These apertures may be circular openings drilled through the rotor as seen in Fig. 7, and the upper end of the rotor may be closed as at 58, in which case the cover plate 54 is held to the rotor by means of a hexagonal head screw 59 threaded into the upper end of the rotor. Alternatively, the upper end of the rotor may be formed with legs and the cover plate held thereto precisely as shown and described in connection with the first embodiment. It will be understood that the upper end of the rotor of the first embodiment may be modified to accord precisely with the arrangement of Fig. 7, that, in other words, the arrangement which provides the discharge apertures and the connection of the cover plate to the rotor may be in accord with Figs. 1-6 or with Fig. 7, regardless of whether the remainder of the construction accords with Figs. 1-6 or with Fig. 7, each having certain advantages which will be apparent to those skilled in the art.

The cover plate 54 may correspond precisely with the corresponding plate 3 of the first embodiment with the sole exception that the openings 33 and 34 of plate 3 are omitted and a central opening 60 is provided, as shown in Fig. 7, to receive screw 59. A stiff but resilient wire retainer element or fixed bearing member 61 holds the rotor assembly in place in the Fig. 7 construction. The wire is formed to have a loop 62 which encircles and clamps onto the sleeve 52 and engages in an external peripheral groove 63 of the sleeve. The wire is thus normally held rigidly to the sleeve subject to removal when desired by springing open the loop 62. The retainer 61, anchored at its portion 62, extends upwardly and outwardly to clear the rotative path of the spinner plate 54 and has a downwardly directed tip

at 64 which is disposed in axial alignment with bore 55 and rotor 53 above the center of plate 54 in position to be engaged by bolt 59 when the rotor and plate are in operative raised position, with water flowing, shown in full lines in Fig. 7. As with the first embodiment, the rotor drops when the water is turned off, the rotor and plate then assuming the lowered positions indicated by broken lines at 65 and 66, respectively. When in lowered position, plate 54 seals against the upper end 67 of sleeve 52 thereby closing bore 55 against entry of dust or dirt. Tip 64 remains stationary upon dropping of the rotor assembly. When the rotor rises as a result of water pressure supplied through stem 51, tip 64 is engaged by a portion of the rotor assembly, such as bolt 59, and serves as a thrust bearing retaining the rotor in sleeve 52. This arrangement, accordingly, provides a thrust bearing between a downwardly facing bearing portion 64 fixed to and comprising an extended part of the stationary sleeve 52 and a rotating, upwardly facing thrust bearing surface or element portion 59 of the rotor, taking the upward thrust of the rotor, and it will be understood that this arrangement of the modification of Fig. 7 serves generally the same function as the internal thrust bearing arrangement, comprising upwardly facing, rotating bearing element 18, 19 and the downwardly facing fixed bearing element 14 of the embodiment shown in Figs. 2 and 3, specifically in that in each case the bearing arrangement permits free rotation of the rotor and limits the upward movement of the rotor to a position in which the discharge apertures are exposed above the upper end of the sleeve.

While only certain preferred embodiments of this invention have been shown and described by way of illustration, many modifications will occur to those skilled in the art and it is, therefore, desired that it be understood that it is intended in the appended claim to cover all such modifications as fall within the true spirit and scope of this invention.

What is claimed as new and what it is desired to secure by Letters Patent of the United States is:

A sprinkler comprising an upright hollow sleeve having an upper end and a lower end and with a vertical cylindrical bore opening through said ends, a hollow cylindrical rotor slideably and rotatively fitted in said bore, said rotor having an upper end portion and a lower end and being slideable from a rest position in which said upper end portion is housed within said bore to an extended active position in which said upper end portion projects above said upper end of said sleeve, a horizontal cover plate fixed to said upper end portion of said rotor in position to rest on said upper end of said sleeve, said upper end portion being provided with outwardly directed discharge outlets arranged below said cover plate and communicating with the hollow interior of said rotor, said cover plate extending outwardly and having downwardly curved end portions spaced outwardly of and opposite respective ones of said discharge outlets, an upwardly facing thrust bearing surface on an upper exterior portion of said rotor and a cooperating fixed bearing member having a resilient band portion supportedly surrounding said sleeve and a bearing portion disposed spacedly above said rotor bearing surface when said rotor is in said rest position and engaged in bearing contact with said bearing surface when said rotor is in said active position, said lower end of said sleeve extending below said lower end of said rotor, and being adapted and arranged for connection to an external water supply source.
